COMBINATION REFLECTOR AND SHOWCASE FRAME

Charles Kenneth Kurtzon, Chicago, Ill., assignor to Garden City Plating & Manufacturing Co., a corporation of Illinois

Application January 3, 1947, Serial No. 720,074

3 Claims. (Cl. 240—6)

1

This invention relates to a combination reflector and showcase frame, and particularly to means for mounting fluorescent or other elongated light tubes for lighting the interior of a showcase.

The present invention comprises a new and compact showcase cornice structure, including a reflector, that can be assembled readily with the rest of the showcase structure. The cornice structure does not detract from the aesthetic appearance of the showcase design and provides a safe conduit for concealed electrical wiring. Additionally, the reflector cooperates with the cornice to hold the top edge of the vertically disposed glass wall securely in position.

The structure by which the various results are attained will be described in connection with the accompanying drawings, in which:

Fig. 1 is a fragmentary perspective view of a showcase embodying the invention;

Fig. 2 is a perspective view showing the cornice and reflector in disassembled position;

Fig. 3 is a detail perspective view showing a socket for receiving one end of a fluorescent light tube;

Fig. 4 is a detail perspective view, similar to Fig. 3, showing a retractable socket for receiving the other end of the fluorescent light tube;

Fig. 5 is a fragmentary cross-sectional view through the top of the showcase showing the reflector secured to the cornice at the top front edge of the showcase;

Fig. 6 is a longitudinal sectional view taken on the line 6—6 of Fig. 5, looking in the direction of the arrows;

Fig. 7 is a longitudinal sectional view taken on the line 7—7 of Fig. 5, looking in the direction of the arrows;

Fig. 8 is a detail perspective view of the end box; and

Fig. 9 is an end elevation showing the end box secured to the reflector.

In the drawings, the reference numeral 2 indicates a showcase of conventional design except for the cornice 3 and the structure associated therewith for lighting the interior of the showcase. Cornice 3 is positioned between adjacent edges of the vertically disposed front glass wall 4 and the top glass wall 5. As seen best in Figs. 2 and 5, the cornice has a longitudinally extending recess 6 at the rear of its bottom portion 7. The top edge of the vertical glass wall 4 fits against the recess 6 and is held against outward or upward movement by the cornice.

The section of the cornice just above the bot-

2

tom portion 7 is rounded, as indicated at 8, to give an attractive appearance to the front top edge of the showcase. The rounded contour merges into a flat top section 9 which is provided at its rear with an offset 10 terminating in a longitudinally extending flange 11. The free edge of top glass wall 5 adjacent the top edge of vertical glass wall 4 rests on flange 11 and abuts offset 10.

10 A flange 12, integral with the cornice, extends angularly from the inner surface of the cornice at approximately the juncture of the rounded section 8 and the flat section 9. The precise position of the flange 12 is not material to the invention, but it is essential that it cooperates with bottom portion 7 and rounded section 8 to form a substantially wedge-shaped space extending along the length of the cornice. Suitably shaped blocks 13 of wood or other suitable material are 15 driven into the wedge-shaped space from either end, to provide an anchoring means for a reflector 14. The edge of block 13 contiguous to the rounded section 8 is wider than the distance between the free end of flange 12 and the top of 20 bottom portion 7. Accordingly, it is impossible for block 13 to be inserted in any other manner, and after the showcase is assembled it is impossible for the block to be removed without dismantling the showcase.

Reflector 14, preferably of the same length as the cornice 3, is secured to block 13 by means of a plurality of screws 15 or similar fastening means. The inside surface of the reflector may be finished in any desirable manner to provide maximum light reflection. In addition to providing adequate light reflection the reflector is utilized to fulfill certain structural requirements, and it is therefore shaped with due consideration for the dual purpose it performs. Both 25 outer edges 16 and 17 are curved or otherwise shaped to fit around opposite sides of an elongated light tube 18 at a proper distance to reflect the light rays downwardly into the showcase.

Preferably the light tube is of small diameter, 30 such as the fluorescent tube sold under the trade-mark "Slimline," for example, so that the sides of reflector 14 are substantially concealed by cornice 3 from the view of a person standing in front of the showcase. It will be obvious that 35 if the showcase is of sufficient length a plurality of light tubes 18 may be mounted in the reflector in axial alignment.

Curved edge 16 of the reflector extends to the line where it engages the rear edge of flange 11 40 of the cornice and then it extends parallel to

flange 11 and flat section 9, as indicated at 19, until it reaches the free end of flange 12. The space between the top surface of reflector section 19, the bottom surface of section 9 of the cornice, offset 10 and flange 12 constitutes a conduit for the passage of wiring 20 which transmits the current to the light tubes. It will be seen, from Fig. 5, that this conduit is fully closed on all sides so that the wiring is fully protected. Section 9 of the cornice, which constitutes one of the walls of the conduit, conceals the wiring from view from the outside of the showcase, and reflector section 19 conceals it from view from inside the showcase.

Curved edge 17 of the reflector terminates in an offset 21 that brings the reflector into contact with the rear surface of vertical glass wall 4. The section 22 of the reflector extends upwardly in contact with glass 4 and supports it to prevent inward movement of the glass. This support of the vertically disposed glass wall by the reflector is of importance because it simplifies the assembly and disassembly of the entire showcase construction. After the vertically disposed glass wall is positioned in recess 6 the reflector may then be secured in position. Since the top glass wall is supported at its adjacent free edge solely by the flange 11 of the cornice it may be positioned either before or after the reflector is secured to the cornice. If the vertical glass wall has to be replaced it is necessary only to remove the reflector and the top glass need not be disturbed.

Section 22 of the reflector engages the rear edge of the bottom portion 7 of the cornice above the recess 6. Sections 22 and 19 of the reflector are joined by a section 23 which extends substantially parallel to the rear edge of blocks 13. The screws 15 pass through section 23 to secure the reflector to the blocks. Preferably section 23 is spaced slightly from the blocks so that they can be tightly drawn against the sides of the wedge shaped space by screws 15 if they do not fit tightly when inserted in the space.

The light tube 18 is mounted in a pair of sockets 24 and 25. The sockets do not constitute part of the present invention. They are described in detail in the copending application of George B. Kurtzon, Serial No. 719,972, filed on even date herewith which matured into Patent No. 2,560,877 on July 17, 1951.

Socket 24 is a fixed socket, and socket 25 has a retractable section 26. A finger piece 27 is secured to section 26 to facilitate its movement. Both sockets are secured to reflector section 23 by means of screws 28. Spacers 29 surrounding each screw 28 are positioned between the reflector and each socket.

An end box 30 is secured to section 19 of the reflector by means of screws 31 passing through apertures 32 in a flange 33 integral with the end box. The bottom wall 34 of the end box is provided with an aperture 35 to which a down tube 36 is secured. The wiring for the fixture is carried to the source of current through the end box and the down tube. This tube is preferably positioned adjacent one corner of the showcase so as to be as inconspicuous as possible.

Although I have described a preferred embodiment of the invention in considerable detail, it will be understood that the description is illustrative, rather than restrictive, as many details of construction may be modified or changed without departing from the spirit or scope of the invention. Accordingly, I do not desire to be restricted to the exact structure described, except as limited by the appended claims.

I claim:

1. In a showcase, a vertically disposed glass plate, a second glass plate extending at an angle to said first mentioned glass, a cornice having a recess fitting against one side of the free edge of said first mentioned glass plate, said cornice having a flange supporting the free edge of said second glass plate, a block secured in said cornice, and a reflector provided with curved edges partially surrounding a space provided for a light tube and an intermediate portion secured to said block, the intermediate portion of said reflector including a flange engaging the other side of the free edge of said first mentioned glass plate and cooperating with said cornice to hold said first mentioned glass plate in position.
2. In a showcase, a cornice having its front edge terminating in a horizontal bottom and having a vertical offset adjacent its rear edge, a flange bisecting the space between said bottom and said offset, said flange cooperating with said bottom and the intermediate portion of said cornice to form a wedge shaped space extending longitudinally of said cornice, a wedge shaped block snugly fitted into said wedge shaped space, and a reflector secured to said block.
3. In a showcase, a cornice having its front edge terminating in a horizontal bottom and having a vertical offset adjacent its rear edge, a flange bisecting the space between said bottom and said offset, said flange cooperating with said bottom and the intermediate portion of said cornice to form a wedge shaped space extending longitudinally of said cornice, a wedge shaped block snugly fitted into said wedge shaped space, a reflector secured to said block, a pair of sockets secured to said reflector, and wiring connecting said sockets electrically, said flange cooperating with said vertical offset, the intermediate portion of said cornice, and the reflector to form a conduit for housing said wiring.

CHARLES KENNETH KURTZON.
